NEEDLE THREADER

Albertus Pretorius, Pretoria, Transvaal,
Union of South AfricaApplication January 3, 1951, Serial No. 204,119
In the Union of South Africa January 5, 1950

6 Claims. (Cl. 223—99)

1

This invention relates to a device to facilitate the threading of needles of the kind used for sewing either by machine or by hand. It is well-known that in the case of needles having a small eye threading often presents difficulties particularly if the eye sight of the user is not as good as it might be.

An object of the present invention is to provide a small compact device by means of which ordinary needles may be threaded rapidly and without difficulty. A further object is to provide a device of robust construction not liable to become deranged and yet relatively inexpensive to make in quantity.

According to the invention there is provided a device for the purpose set forth comprising a strip, wire or like member of a form bifurcated towards one end into resiliently separated limbs and over the other end of which the eye of the needle may be passed and removed from the bifurcated end, a body in which said member is loosely encaged against removal, and which is provided with a lateral aperture following the general form of said bifurcated member and means for guiding the needle eye therover and from end to end of said aperture, a further aperture in said body enabling the thread to be admitted into the bifurcation of said member to be gripped between the said limbs whilst the needle eye is passed therover, and means for retaining the thread thus passed through the needle until the latter leaves or is about to leave the body.

The said member may be encaged in the body in a generally hairpin bend shape with portions of said limbs resiliently held together and the said other end exposed in said aperture for easy acceptance into the needle eye applied thereto, the said further aperture extending into the body to a region opposite to said resiliently held portions of the bifurcated member limbs for the gripping of the thread.

The said limbs of said member may be of unequal lengths, one extending further towards the adjacent end of the first mentioned aperture than does the other and executing an S-like curve so designed as when traversed by the needle eye to release the grip of said limbs upon the thread and facilitate its being withdrawn from the body after the needle has passed over it.

Means may be provided for catching the loop of thread from the eye of the needle before the latter leaves the said body, such for instance, as hook or like means at an appropriate region or regions of the body and/or one of the limbs aforesaid beyond the region thereof into which the thread is admissible.

2

The invention further comprises the specific construction of needle-threading device and its modifications as hereinafter indicated.

The appended sheet of drawings illustrates the present preferred construction of the device, and in these drawings, which are to a substantially enlarged scale compared with the actual device which may be of substantially no greater bulk than enables it to be held easily between the fingers of one hand whilst the other hand is used for applying the thread and passing the needle over it:

Figure 1 is an elevation of the device as it appears for example when held at region x between thumb and forefinger of the left hand;

Figure 2 is a sectional view, or view with a "front" lamination removed;

Figure 3 is a cross section on the line and in the direction of arrows III—III of Figure 1; and

Figure 4 is a side view of the aforesaid bifurcated member in relaxed condition, i. e. removed from the body of the device.

Referring to the drawings, the body is formed from any suitable material, e. g. metal or one of the so called "plastics" in three laminations 1, 2 and 3 and the central one of these provides a chamber 2a in which a spring steel or like member 4 is encaged after resilient deformation from its relaxed form shown in Figure 4.

Member 4 is bent to the form shown, from springy steel ribbon of a fine enough gauge and width that the eye of a needle may pass over it from the closed end 5 which is suitably pointed, the limbs 5a and 6 closing resiliently together to allow of this movement of the needle, and the needle finally leaving the longer limb at 8 after traversing the S-shaped portion 7.

In position in the body chamber the member 4 presents end 5 somewhat beyond of the edge face 9 of lamination 2 so that when the eye end of the needle is applied endwise against face 10 of lamination 3 and slid towards the right hand side of the drawings, the eye aperture is readily passed over the end 5. Surfaces 9 and 10 turn into the first curved portion 11 of the chamber and follow the generally hairpin curve 12 shown. The lamination 1 is apertured as at 14 to allow the neck of the needle then to traverse the body aperture and leave it at opening 13, the surface 10 and its continuation to 10a forming a continuous floor for guidance of the needle eye throughout its passage over the member 4 and out at 13. Surface 10 and its continuation to 10a are preferably of shallow groove form as shown in Figure 3, assisting the guidance of the needle eye.

The member 4 being for a substantial part of its length exposed through aperture 14, and only

limbs 5a and 6, including portion 7, covered by the lamination 1, in order to prevent inadvertent extraction of the member 4 from the body as the needle is traversing it, a small lobed or equivalent, e. g. pointed star wheel 15 freely pivoted at 15a in parts 1 and 2 as shown is accommodated in a pocket 15b to overlap the member 4 at both sides of the curved portion 12. The lobes or points yield freely as gates to the passage of the needle eye over the member 4.

In the part 3 of the body a straight, slit-like aperture 16 extends along one edge of the grooved surface 10a (and therefore out of line with the opposed aperture 14) from adjacent the opening 13 to just short of opposite to the wheel pivot 15a, so that a thread (stretched in a direction through the plane of Figures 1 and 2 of the drawings) may be entered at 13 and passed into the bight between portions 5a and 6 of the member 4, which portions are resiliently gripped together as shown in Figures 1 and 2. By this means the thread is held whilst the eye of the needle passes over it and a loop remains thus gripped. Just after this point the tail portion 6a of limb 6 is contracted by the eye on to the S-portion 7 causing parts 5a and 6 to spring apart behind the eye to release the thread loop which can then move towards the end 13. Whilst the needle can then be withdrawn the thread loop following it catches hookwise on the point of a small fixed finger piece 17 which projects into the path necessarily taken by the thread in following the needle. Thus caught, the loop may be drawn to any length convenient to the user and if desired until the free or short end of thread leaves the eye and escapes; the needle then being properly threaded for use.

Grip between parts 5a and 6 may be enhanced by slight roughening of their engageable surfaces, or by providing one or more distinct teeth, fine serrations or the like on one engageable in complementary teeth or openings in the other.

Similarly the finger 17 may be replaced by a correspondingly functioning small tooth or hook upstanding from the limb 5a between the portions 7 and 8.

The entrances to the chamber at 10 and 13 and to the slit 16 are preferably throated, and generally all edges are rounded or smoothed off for ease of manipulation of the device.

The member 4 may, if desired, be made in several portions suitably joined together; e. g. a single thickness piece of spring steel extending from the end 5 to or somewhat beyond the hairpin bend which occupies portion 12 in the body, where bifurcation commences into portions 5a and 6a which, or one of which, may be welded or otherwise joined to the single piece. Whether the member 4 is or is not a single piece of material it is preferred that from point 5 to the hairpin bend or turn the material is in effect a single thickness.

The body may, if desired, be moulded to shape in one of the well-known "plastics," the design being adapted as may be necessary or desirable to permit such methods of production, which may, for instance, enable the above described laminar construction to be reduced to a main portion whereof part 1 constitutes a simple cover suitably applied and secured over a single piece combining parts 2 and 3.

I claim:

1. A device for the purpose set forth comprising a resilient wire member of a form pointed at

one end to enable it to be passed into the eye of the needle and bifurcated towards the other end into resiliently separated limbs and over the said pointed end of which the eye of the needle may be passed, moved along the said member and removed from the bifurcated end thereof, a body containing a recess in which said member is loosely engaged against removal, and which body is provided with a lateral aperture following the general form of said bifurcated member in communication with the recess in which said member is loosely engaged and containing means for guiding the needle eye over said member and from end to end of said aperture, the body being formed with a further aperture into the recess which further aperture is located adjacent and communicates with that region of the said recess which accommodates the bifurcated end of the resilient member and is grooved enabling the thread to be admitted into the bifurcation of said member to be gripped between the said limbs whilst the needle eye is passed thereover, and means for retaining the thread thus passed through the needle until the latter leaves or is about to leave the body.

2. A device according to claim 1, wherein the said member is engaged in the body in a generally hairpin bend shaped recess with portions of said limbs resiliently held together and the said pointed end exposed in the said aperture for easy acceptance into the needle eye applied thereto, the said further aperture extending into the body to a region opposite to said resiliently held portions of the bifurcated member limbs for the gripping of the thread.

3. A device according to claim 1, wherein the said limbs of the said member are of unequal lengths, one extending further towards the adjacent end of the first mentioned aperture than does the other and executing an S-like curve so designed as when traversed by the needle eye to release the grip of the said limbs upon the thread and facilitate its being withdrawn from the body after the needle has passed over it.

4. A device according to claim 2, wherein the said limbs of the said member are of unequal lengths, one extending further towards the adjacent end of the first mentioned aperture than does the other and executing an S-like curve so designed as when traversed by the needle eye to release the grip of the said limbs upon the thread and facilitate its being withdrawn from the body after the needle has passed over it.

5. A device according to claim 1, comprising means for catching the loop of thread from the eye of the needle before the latter leaves the said body, such means including hook means at an appropriate region of the body and/or one of the limbs aforesaid beyond the region thereof into which the thread is admissible.

6. A device according to claim 4, comprising means for catching the loop of thread from the eye of the needle before the latter leaves the said body, said means comprising hook means fixed in the body beyond the region of the said limbs in the direction in which the needle traverses the said member into which the thread is admissible.

ALBERTUS PRETORIUS.
